UNITED STATES PATENT OFFICE

149,416

DESIGN FOR A DESK

Charles E. Jones, Chicago, Ill.

Application December 6, 1946, Serial No. 135,319

Term of patent 14 years

(Cl. D33—7)

To all whom it may concern:

Be it known that I, Charles E. Jones, a citizen of the United States, residing at Chicago, in the county of Cook and State of Illinois, have invented a new, original, and ornamental Design for a Desk, of which the following is a specification, reference being had to the accompanying drawing, forming a part thereof.

In the drawing:

Fig. 1 is a perspective view of a desk, showing my new design;

Fig. 2 is a rear elevation;

Fig. 3 is an end elevation;

Fig. 4 is another perspective view; and

Fig. 5 is a top plan view.

I claim:

The ornamental design for a desk, substantially as shown.

CHARLES E. JONES.
